CHARLES R. SHORT AND CALEB E. SUMMERS, OF DETROIT, MICHIGAN, ASSIGNEES TO
GENERAL MOTORS CORPORATION, OF DETROIT, MICHIGAN, A CORPORATION OF
DELAWARE.

FUEL-SUPPLY DEVICE FOR INTERNAL-COMBUSTION ENGINES.

Application filed May 31, 1919. Serial No. 301,076.

To all whom it may concern:

Be it known that we, CHARLES R. SHORT and CALEB E. SUMMERS, citizens of the United States, both residents of Detroit,

5 Wayne County, State of Michigan, have invented certain new and useful Improvements in Fuel-Supply Devices for Internal Combustion Engines, of which the following is a specification.

10 Our invention relates to carbureting devices designed for use with internal combustion engines, and particularly to carbureting devices designed for use with liquid fuels which require a considerable 15 amount of heat to accomplish their vaporization and the production of a gaseous mixture such, for example, as kerosene.

The objects of our invention are to provide a carbureting device of the class referred to with improved means for vaporizing the liquid fuel employed; to provide a carbureting device in which the temperature of the vaporized fuel and of the air with which it is mixed is kept as low as practicable, to 25 thereby secure increased volumetric efficiency of the engine; to provide a carbureting device in which a gaseous mixture better adapted for use when the engine is running under light load, or idling, will be produced than has heretofore usually been the case; to provide a device wherein the mixture producing function and the functions performed by intake and exhaust manifolds are combined in a single structure; and to provide 30 improvements in and relating to various of the elements and features present in and forming a part of carbureting devices of the type or class to which our invention relates.

40 With the above and other objects in view, our invention consists in the improved carbureting device illustrated in the accompanying drawings, described in the following specification, and particularly claimed, 45 and in such variations and modifications thereof as will be obvious to those skilled in the art to which our invention relates.

In the drawings accompanying and forming a part of this specification, and wherein the preferred embodiment of our invention is illustrated:

50 Figure 1 is a view illustrating our improved carbureting device in side elevation, and embodied in a structure wherein the ele-

ments whereby the vaporization of the liquid 55 fuel is accomplished are combined with the intake and exhaust manifolds of the engine with which the device is used.

Figure 2 is a view showing a section of our invention taken upon a vertically extending transverse plane indicated by the line II, II, Figure 1.

Figure 3 is a view illustrating our invention in plan, certain portions of the exterior casing thereof being broken away to better 65 show features of internal construction;

Figure 4 is a view showing a section upon a vertically extending plane indicated by the line IV, IV, Figure 3.

Figure 5 is a view showing the vaporizing 70 plate of our device by itself; and

Figure 6 is a view showing a section taken upon an inclined plane indicated by the line VI, VI, Figure 4.

Referring now to the drawings, the reference numeral 5 designates an exhaust manifold of any suitable type, style or construction, but which is illustrated as having four passages indicated by the reference numerals 6 leading thereto, and which passages are designed to communicate with a like number of exhaust passages provided in the engine with which our device is used, so that the exhaust gases may flow into said manifold, and out therefrom 80 through an outlet passage 7 and an exhaust pipe 8. The peripheral wall of the said manifold is provided with a substantially vertical and flat or plane portion, the location of which is indicated by the reference numerals 9, Figure 1, and this flat portion is provided with an opening 10 adapted to receive and accommodate a vaporizing plate which is heated by the exhaust gases flowing through the manifold, and which plate 95 serves to vaporize the liquid fuel and produce a gaseous mixture whereby the engine is operated.

The reference numeral 11 designates a suitable casing illustrated as in the form 100 of a supply or intake manifold having an air inlet passage 12 leading thereto, and one or more outlet branches or passages 13 leading therefrom and adapted to communicate with the inlet passages of the engine 105 with which the device is used, the structure of the said manifold or casing being likewise capable of variation in order to

adapt it to the particular type of engine with which our device is to be used, as will be appreciated.

The intake manifold is shown as having a vertically extending portion into the lower end of which the inlet passage 12 leads, and from the upper end of which the outlet passage or passages aforesaid extend to the engine; and the interior of said manifold provides a mixing chamber at about the place indicated by the reference numeral 14 in Figure 2, and, in the embodiment of our invention illustrated, a branch passage 15 is provided in the wall thereof, the said passage communicating with the air inlet 12 and serving to supply air for atomizing the fuel used in our device preparatory to the vaporization thereof, as will hereinafter appear. The intake manifold is provided with a vertically extending flat side wall 16, as best shown in Figure 2, which wall is adapted to extend over the opening 10 aforesaid provided in the exhaust manifold, and with a flange 17, see Figures 1 and 3, adapted to extend about the said opening; and the said manifold is held in place by cap screws 18 extending through the flange 17, and by yokes 19 held in place by cap screws 20 extending into the engine, so that the same may be removed independently of the exhaust manifold, the latter being secured in place by cap screws 21 extending into the engine, as will be understood.

The reference numeral 22 designates a vaporizing plate located within the opening 10 provided in the exhaust manifold, and which plate is preferably secured to the flat surface or side wall 16 provided upon the intake manifold as by means of a series of screws arranged about the periphery thereof and extending through holes 23, see Figure 5, so that the vaporizing plate will be removed along with the manifold when the latter is removed, as above explained. The said vaporizing plate is provided with a recess in one of its surfaces whereby a vaporizing chamber 24 is provided between the same and the wall 16, and with a plurality of heat conducting fins 25 upon the opposite side thereof which are exposed to the hot gases passing through the exhaust manifold, to thereby secure a more effective heating of the vaporizing plate.

A vertically extending heating passage 26 is provided in the plate 22, the lower end of said passage being in communication with the vaporizing chamber 24 through an opening 27, and the upper end thereof being placed in communication with the interior of the intake manifold and with the mixing chamber 14 therein, as by means of a passage 28. The rate of flow through the passage 28 may be controlled in any way, as by means of an adjustable needle valve 29. The vaporizing chamber 24 is arranged

substantially vertically, as best shown in Figure 2, and the suction of the engine when the device is in use induces a flow of air through the passage 15 and past a fuel supply nozzle 30, whereby the liquid fuel employed is atomized, the mixture of air and fuel thus produced flowing through a tube 31 extending through the supply manifold in the embodiment of our invention illustrated and which tube, in connection with the passage 15 and the fuel supply nozzle provides a fuel supply conduit discharging into the vaporizing chamber adjacent the upper end thereof.

The stream of air and fuel supplied so through the fuel supply conduit aforesaid is directed against the heated vertically extending inner surface or wall of the vaporizing plate, and wets and runs down the same to a greater or less extent depending, obviously, upon the rapidity with which the liquid fuel intercepted by the plate is vaporized, the fuel in question passing off from the heated surface, whereby its vaporization is accomplished, into the comparatively large vaporizing chamber as fast as it is vaporized by heat derived from the vaporizing plate, as will be appreciated, the average temperature within said vaporizing chamber being materially lower than the temperature of the vaporizing plate because of the relative location of the parts of our device and the continuous flow of air and fuel therethrough.

The lower end of the vaporizing chamber is placed in communication with an annular passage 32 formed, preferably, in the exterior surface of a Venturi tube 33 located in the air inlet passage 12, by means of an opening 34, and the vaporized liquid fuel and the air which is mixed therewith flow from the passage 32 through openings 35 in the venturi, and mix with additional air entering through the air supply passage 12, the opening 34, the annular passage 32, and the openings 35 providing a permanently open passage leading from the lower end of the vaporizing chamber and discharging into the air supply passage. The completion of the mixing of the rich preliminary mixture thus provided with the diluting air to form a proper combustible mixture is accomplished in the mixing chamber 14, and as the mixture flows along the passage or passages leading to the engine, as will be understood.

The flow through the carburetor casing or intake manifold is controlled by a suitable throttle valve to thereby regulate the operation of the carburetor and the speed of the engine with which the same is used. In the embodiment of our invention illustrated the throttle valve is located in the vertically extending portion of the carburetor casing, and between the points at

which the passage leading from the lower end of the vaporizing chamber discharges into the air supply passage 12 and the point at which the passage 26 discharges into the 5 casing through the passage 28, the said throttle valve being designated by the reference numeral 36, and the same being shown as of the ordinary butterfly type, although any kind or type of throttle valve 10 may be used so long as it is suitable for the purpose of controlling the flow through the carburetor casing or intake manifold.

Liquid fuel is supplied to the nozzle 30 through a fuel supply passage 37 leading 15 from a fuel reservoir 38, which reservoir is supplied through a fuel supply pipe 39, and within which reservoir a constant level of liquid fuel is maintained by a valve 40 controlled by float 41, by an overflow device, or otherwise.

The rate of flow through the fuel supply conduit 37 is regulated by a rotary controlling member 42 housed in a passage provided in a boss 43 formed on the side wall of 25 the fuel reservoir 38, see Figure 4, which rotating member is provided with a central passage 44, with which a plurality of separate passages 45 differing in size one from another, see Figure 2, communicate, and 30 any one of which passages may be brought into a position to establish a communication between the passage 37 and the nozzle 30 by rotating the member 42. This construction provides in effect a plurality, four in the 35 embodiment of our invention illustrated, of fuel supply passages any one of which may be used independently of the others, the operator being thus enabled to regulate the supply of liquid fuel throughout wide limits and according to the speed and load conditions under which the engine is operating, 40 although he cannot shut off the supply entirely for the rotating member 42 is arrested and held in positions such that an opening 45 registers with the fuel supply passage 37 by means of a spring-pressed stop or catch 46 in engagement with the recesses 47 provided in the member 42, and having inclined sides, as illustrated in Figure 6 of the 50 drawings.

The fuel supply reservoir is secured to the supply manifold by means of cap screws 48 or equivalent securing means so that the same may be readily removed from the supply manifold, or removed therewith when the latter is removed as hereinbefore explained, as will be appreciated, the said manifold being provided with a suitable boss 49 to facilitate the securing of the fuel supply reservoir thereto, as best shown in Figure 3.

While in the foregoing description of our carbureting device we have referred frequently to the intake and exhaust manifolds present in the preferred embodiment of our

invention illustrated, and in which embodiment the elements concerned with the production of the combustible mixture are merged with the manifolds in question, our invention, considered in its broader aspect 70 and merely as a device for providing a combustible mixture, is by no means limited to a structure in which elements whereby the mixture forming function and the functions performed by intake and exhaust manifolds are combined and form a single structure of such form, shape, and outline as to provide for all of said functions, although the more restricted and specific form of our invention does comprehend a single structure having 75 means for producing a combustible mixture, and having a form, shape and arrangement of the parts such that intake and exhaust manifolds for the engine are present in such structure. We have, therefore, in the broader claims wherein the distinguishing features of our invention are enumerated 80 defined the invention as comprising a casing, together with other elements and features whereby a carbureting device is provided, while in the more specific claims the casing takes the form of an intake manifold, as illustrated in the drawings, and the elements which collectively form the device, 85 regarded in its more comprehensive aspect, 90 provide also the intake and exhaust manifolds for the engine, in addition to means for producing a combustible mixture for use therein.

When our improved carbureting device is 100 in use, and assuming that the throttle valve is open so as to permit a free flow through the intake manifold or carburetor casing, the suction produced by the engine induces a flow of air through the fuel supply conduit formed by the air passage 15 and the tube 31, and into the vaporizing chamber 24, the liquid fuel being entrained by the air as it flows past the fuel nozzle 30.

The liquid fuel thus supplied to the vaporizing chamber is vaporized therein, and the rich preliminary mixture thus formed flows from the chamber through the opening 34, passage 32, and openings 35 into the main stream of air entering the casing through the air inlet passage 12, and mixes therewith as the mixture flows toward the engine.

If now the throttle valve 36 is moved toward its closed position the quantity of mixture flowing through the intake manifold and to the engine is reduced, and, as such valve reaches or approaches its completely closed condition, a flow of air and vaporized fuel from the vaporizing chamber 24, and of air through the air inlet passage 12, openings 35, passage 32 and opening 34, will be established through the opening 27 and upwardly along the passage 26, and through the passage 28 and into the 130

carburetor casing, the greater part if not the entire quantity of the mixture flowing to the engine when the throttle valve is closed or nearly closed taking place through the 5 passage 26 in the vaporizing plate, although it will be appreciated that the volume of mixture thus supplied to the engine is much less than is the case when the throttle valve is open, at which time little or no mixture 10 flows through the passage 26 and into the upper end of the carburetor casing.

The throttled condition above mentioned is obviously that which is present when the engine is operating without load, or idling, 15 during which time the quantity of combustible mixture flowing to the engine is comparatively small. The proportion of fuel present in said mixture, however, is increased in our device as the throttle valve 20 approaches its closed position, in order to thereby insure a more certain ignition, and a more complete burning of the mixture under the lower maximum compression pressure conditions resulting from the reduced 25 quantity of mixture entering the engine cylinders, this increase in the quantity of fuel supplied being due to the fact that the reduced flow of air through the restricted openings 35 is accomplished by an inordinate fall of pressure within the carburetor 30 casing, which reduction of pressure results in an increased suction effect at the fuel nozzle 30 over that present at said nozzle when the throttle valve is open, which increase in suction at the nozzle results in an 35 increased flow of fuel therethrough, as will be understood.

The valve 29 is used to adjust the carbureting device to the engine with which it 40 is used so that the engine will run properly or idle at low speed, and under reduced or no load conditions, and the passage 26 through which the mixture flows to supply the engine when idling is so disposed that 45 it may be heated, as by arranging said passage in the vaporizing plate, because at such times the exhaust gases are much cooler than when the engine is operating under normal load conditions and with full 50 charges, which lack of heat may result in incomplete vaporization of the fuel in the vaporizing chamber. Such incomplete vaporization, however, is completed or more nearly completed by causing the mixture 55 to flow through the heated passage 26, whereby a proper combustible mixture for use when idling, or when operating with the throttle valve closed to a considerable extent, is secured.

The liquid fuel, being discharged into the vaporizing chamber 24 at the upper end thereof and against the vaporizing plate 22, 60 wets the plate and runs down the same until it is vaporized, there being no accumulation of liquid fuel within the vaporizing chamber

or carburetor casing when our device is in use. Such vaporization is obviously progressive, the more volatile constituents of the fuel being vaporized very soon after the fuel reaches the plate, while the greater heating 70 effect due to longer contact with the plate as it runs down the same may be necessary to vaporize the less volatile portion of the fuel. As to all parts of the fuel, however, the vapors produced by their vaporization 75 pass from the plate immediately upon being produced and mingle with the contents of the vaporizing chamber, the average temperature of which is much lower than the temperature of the vaporizing plate. 80

The lower temperature within the vaporizing chamber as compared with the temperature of the vaporizing plate is due to the structural features of our device wherein the vaporizing chamber is located 85 between the vaporizing plate and the much cooler mixing chamber, and to the features of design, construction, arrangement and operation of the vaporizing plate itself, it being obvious that in designing the device 90 it is necessary to provide only for a temperature of the vaporizing plate sufficiently high to vaporize the thin film of liquid fuel which flows down the surface thereof, as distinguished from providing for heating 95 the entire volume of the chamber to the vaporizing temperature, as would be necessary if the atomized liquid fuel was to be vaporized by conduction of heat from one particle to another throughout the mass 100 thereof, as has heretofore commonly been the case. It therefore follows that the temperature of the rich preliminary mixture 105 which flows from the vaporizing chamber is much lower than the temperature necessary to accomplish the vaporization of the liquid fuel, and that the combustible mixture produced by mixing additional air with such preliminary mixture is at a still lower temperature because of the cooling 110 effect of the diluting air, from which it will be appreciated that the quantity or mass of combustible mixture entering the cylinders upon the suction strokes of the pistons will be increased, and high volumetric efficiency 115 of the engine thereby secured.

In view of the fact that an enriched mixture is desirable, if indeed not necessary, at starting, it will be appreciated that an engine equipped with our improved carbureting device may be readily started, the throttle valve being closed at such time and the mixture produced being a much enriched mixture, because of the fact that increased suction effect will be produced at the fuel 125 supply nozzle over that which would be present thereat if air could enter the carburetor casing freely through the air inlet 12. In fact the presence of the enriched mixture, together with the more effective 130

atomization which results from a strong flow past the fuel supply nozzle, provides a scheme whereby the engine may ordinarily be started cold, and with kerosene as a fuel.

- 5 As changes of construction could be made within the scope of our invention, it is intended that all matter contained in the above description or shown in the accompanying drawings shall be interpreted as illustrative 70 and not in a limiting sense; the distinguishing features of our invention being particularly pointed out in the following claims.
- 10 Having thus described and explained our invention, we claim and desire to secure by 75

15 Letters Patent—

1. In a carbureting device for internal combustion engines, a casing having an air inlet passage leading thereinto and a mixture outlet passage leading therefrom, a vaporizing chamber, means for heating said vaporizing chamber, means for supplying atomized liquid fuel to said vaporizing chamber to be vaporized therein, a passage leading from said vaporizing chamber and 80 discharging into said air inlet passage, a passage leading from said vaporizing chamber and discharging into said casing, and a throttle valve for controlling the flow through said casing.

2. In a carbureting device for internal combustion engines, a casing having an air inlet passage leading thereinto and a mixture outlet passage leading therefrom, a vaporizing chamber, means for heating said vaporizing chamber, means for supplying atomized liquid fuel to said vaporizing chamber to be vaporized therein, a passage leading from said vaporizing chamber and discharging into said air inlet passage, a 85 passage leading from said vaporizing chamber and discharging into said casing adjacent the mixture outlet passage leading therefrom, means for heating said last mentioned passage, and a throttle valve for controlling the flow through said casing.

3. In a carbureting device for internal combustion engines, a casing having a vertically extending portion, an air inlet passage leading into the lower end thereof, and a mixture outlet passage leading from the upper end of said casing, a vertically extending vaporizing chamber the lower end of which is in permanently open communication with said air inlet passage, a passage leading from said vaporizing chamber and discharging into said casing adjacent the upper end thereof, means for supplying atomized liquid fuel to the upper end of said vaporizing chamber, and a throttle valve for 90 controlling the flow through said casing.

4. In a carbureting device for internal combustion engines, a casing having a vertically extending portion, an air inlet passage leading into the lower end thereof, and a mixture outlet passage leading from the up-

per end of said casing, a vertically extending vaporizing chamber the lower end of which is in permanently open communication with said air inlet passage, a passage leading from the lower end of said vaporizing chamber and discharging into said casing adjacent the upper end thereof, means for heating said passage, means for supplying atomized liquid fuel to the upper end of said vaporizing chamber, and a throttle valve for controlling the flow through said casing.

5. In a carbureting device for internal combustion engines, a casing having an air inlet passage leading thereinto and a mixture outlet passage leading therefrom, a throttle valve for controlling the flow through said casing, a vaporizing chamber, means for heating said vaporizing chamber, means for supplying liquid fuel to said vaporizing chamber to be vaporized therein, a passage leading from said vaporizing chamber and discharging into said air inlet passage between said throttle valve and the external atmosphere, and a passage leading from said vaporizing chamber and discharging into said casing between said throttle valve and the engine with which the device is used.

6. In a carbureting device for internal combustion engines, a casing having a vertically extending portion, an air inlet at the lower end and a mixture outlet at the upper end of said casing, and a throttle valve located between said inlet and outlet, a vertically extending vaporizing chamber the lower end of which is in permanently open communication with said air inlet, a passage leading from said vaporizing chamber and discharging into said casing above said throttle valve, and means for supplying liquid fuel to the upper end of said vaporizing chamber.

7. In a carbureting device for internal combustion engines, a casing having a vertically extending portion, an air inlet at the lower end and a mixture outlet at the upper end of said casing, and a throttle valve located between said inlet and outlet, a vertically extending vaporizing chamber the lower end of which is in permanently open communication with said air inlet, a passage leading from the lower end of said vaporizing chamber and discharging into said casing above said throttle valve, means for heating said passage, and means for supplying liquid fuel to the upper end of said vaporizing chamber.

8. In a carbureting device for internal combustion engines, a casing having an air inlet passage leading thereinto and a mixture outlet passage leading therefrom, a throttle valve for controlling the flow through said casing, a vaporizing chamber, means for heating said vaporizing chamber,

- an air supply conduit leading into said vaporizing chamber, a fuel supply nozzle discharging into said air supply conduit, a passage leading from said vaporizing chamber and discharging into said air inlet passage between said throttle valve and the external atmosphere, and a passage leading from said vaporizing chamber and discharging into said casing between said throttle valve and the engine with which the device is used.
9. In a carbureting device for internal combustion engines, a casing having a vertically extending portion, an air inlet at the lower end of said casing, and a mixture outlet passage at the upper end thereof, a throttle valve located in said vertically extending portion, a vertically extending vaporizing chamber the lower end of which is in permanently open communication with said air inlet, a passage leading from said vaporizing chamber and discharging into said casing above said throttle valve, an air supply conduit leading from said air inlet and discharging into said vaporizing chamber, and a fuel supply nozzle discharging into said air supply conduit.
10. In a carbureting device for internal combustion engines, a casing having a vertically extending portion, an air inlet at the lower end of said casing, and a mixture outlet passage at the upper end thereof, a throttle valve located in said vertically extending portion, a vertically extending vaporizing chamber the lower end of which is in permanently open communication with said air inlet, a passage leading from the lower end of said vaporizing chamber and discharging into said casing above said throttle valve, means for heating said passage, an air supply conduit extending through said casing and discharging into the upper end of said vaporizing chamber, and a fuel supply nozzle past which the air flowing through said conduit flows.
11. In a carbureting device for internal combustion engines, an exhaust manifold having a wall provided with an opening, an intake manifold secured to said exhaust manifold, a vaporizing plate located within said opening, a portion of said intake manifold cooperating with said vaporizing plate to form a vaporizing chamber which is in communication with the inlet end of said intake manifold, a fuel supply conduit discharging into said vaporizing chamber, and a fuel supply nozzle discharging into said fuel supply conduit.
12. In a carbureting device for internal combustion engines, an exhaust manifold having a wall provided with an opening, an intake manifold secured to said exhaust manifold, a vaporizing plate located within said opening, a portion of said intake manifold cooperating with said vaporizing plate to form a vaporizing chamber the lower end of which is in permanently open communication with the inlet end of said intake manifold, a fuel supply conduit discharging into said vaporizing chamber, a fuel supply nozzle discharging into said fuel supply conduit, a passage leading from the lower end of said vaporizing chamber and discharging into said intake manifold adjacent the upper end thereof, means for heating said passage, and a vaporizing chamber the lower end of which is in permanently open communication with the inlet end of said intake manifold, a fuel supply conduit discharging into the upper end of said vaporizing chamber, a fuel supply nozzle discharging into said fuel supply conduit, a passage leading from the lower end of said vaporizing chamber and discharging into said intake manifold adjacent the upper end thereof, and a throttle valve located between the discharge end of said last mentioned passage and the inlet to the said intake manifold.
13. In a carbureting device for internal combustion engines, an exhaust manifold having a vertically disposed wall provided with an opening, an intake manifold secured to said exhaust manifold and having a wall extending across the opening aforesaid, a vaporizing plate located within said opening and having a recess whereby a vaporizing chamber is provided, and the lower end of which vaporizing chamber is in permanently open communication with the inlet end of said intake manifold, a fuel supply conduit discharging into the upper end of said vaporizing chamber, and a fuel supply nozzle discharging into said fuel supply conduit.
14. In a carbureting device for internal combustion engines, an exhaust manifold having a vertically disposed wall provided with an opening, an intake manifold secured to said exhaust manifold and having a wall extending across the opening aforesaid, a vaporizing plate located within said opening and secured to said intake manifold and having a recess whereby a vaporizing chamber is provided, and the lower end of which vaporizing chamber is in permanently open communication with the inlet end of said intake manifold, a fuel supply conduit extending through said intake manifold and discharging into the upper end of said vaporizing chamber, and a fuel supply nozzle discharging into said fuel supply conduit.
15. In a carbureting device for internal combustion engines, an exhaust manifold having a vertically disposed wall provided with an opening, an intake manifold secured to said exhaust manifold and having a wall extending across the opening aforesaid, a vaporizing plate located within said opening and having a recess, said wall covering said recess and thus providing a vaporizing chamber, and the lower end of which vaporizing chamber is in permanently open communication with the inlet end of said intake manifold, a fuel supply conduit discharging into the upper end of said vaporizing chamber, a fuel supply nozzle discharging into said fuel supply conduit, a passage leading from the lower end of said vaporizing chamber and discharging into said intake manifold adjacent the upper end thereof, means for heating said passage, and a vaporizing chamber the lower end of which is in permanently open communication with the inlet end of said intake manifold, a fuel supply conduit discharging into the upper end of said vaporizing chamber, a fuel supply nozzle discharging into said fuel supply conduit, a passage leading from the lower end of said vaporizing chamber and discharging into said intake manifold adjacent the upper end thereof, and a throttle valve located between the discharge end of said last mentioned passage and the inlet to the said intake manifold.

a throttle valve for controlling the flow through said intake manifold.

16. In a carbureting device for internal combustion engines, an exhaust manifold 5 having a vertically disposed wall provided with an opening, an intake manifold secured to said exhaust manifold and having a wall extending across the opening aforesaid, a vaporizing plate located within said opening 10 and having a recess covered by the said wall of the intake manifold whereby a vaporizing chamber is provided, and the lower end of which vaporizing chamber is in permanently open communication with the inlet end of 15 said intake manifold, a fuel supply conduit discharging into the upper end of said vaporizing chamber, a fuel supply nozzle discharging into said fuel supply conduit, a passage leading from the lower end of said 20 vaporizing chamber through said vaporizing plate and discharging into said intake manifold adjacent the upper end thereof, a valve for controlling the flow through said passage, and a throttle valve located between 25 the discharge end of said passage and the point at which the lower end of the vaporizing chamber communicates with the inlet of said intake manifold for controlling the flow therethrough.
- 30 17. In a charge forming device for internal combustion engines, a vaporizing plate having a recess adapted to provide a vaporizing chamber, a plurality of fins projecting from said plate, and a heating passage formed in said plate and communicating with said recess.
- 35 18. In a charge forming device for internal combustion engines, a vaporizing plate having a recess adapted to provide a vaporizing chamber, and a heating passage 40
- 45 19. In a charge forming device for internal combustion engines, a vaporizing plate having a recess adapted to provide a vaporizing chamber, a plurality of fins projecting from said plate, and a heating passage formed in said plate and one end of which passage is in communication with one 50 end of said recess.
- 55 20. In a charge forming device for internal combustion engines, a vaporizing plate having a recess in one of its sides adapted to provide a vaporizing chamber, and a plurality of fins upon the side thereof opposite said recess.
- 60 21. In a charge forming device for internal combustion engines, a vaporizing plate having a recess in one of its sides 65 adapted to provide a vaporizing chamber, and a heating passage extending through said plate and communicating with said recess.
- 65 22. In a charge forming device for internal combustion engines, a vaporizing plate having a recess in one of its sides 70 adapted to provide a vaporizing chamber, a plurality of fins extending from the surface of said plate which is opposite said recess, and a heating passage extending through said plate and located between said fins and said recess and one end of which passage is in communication with one end 75 of said recess.

formed in said plate and one end of which passage is in communication with one end of said recess.

7 19. In a charge forming device for internal combustion engines, a vaporizing plate having a recess adapted to provide a vaporizing chamber, a plurality of fins projecting from said plate, and a heating passage formed in said plate and one end of which passage is in communication with one 50 end of said recess.

20. In a charge forming device for internal combustion engines, a vaporizing plate having a recess in one of its sides 55 adapted to provide a vaporizing chamber, and a plurality of fins upon the side thereof opposite said recess.

21. In a charge forming device for internal combustion engines, a vaporizing plate having a recess in one of its sides 60 adapted to provide a vaporizing chamber, and a heating passage extending through said plate and communicating with said recess.

22. In a charge forming device for internal combustion engines, a vaporizing plate having a recess in one of its sides 65 adapted to provide a vaporizing chamber, a plurality of fins extending from the surface of said plate which is opposite said recess, and a heating passage extending through said plate and located between said fins and said recess and one end of which passage is in communication with one end 70 of said recess.

In testimony whereof, we affix our signatures.

CHARLES R. SHORT.
CALEB E. SUMMERS.
